FUEL STORAGE SYSTEM

Gilbert J. C. Andresen, Stow, Ohio, assignor to The Goodyear Tire & Rubber Company, Akron, Ohio, a corporation of Ohio

Filed Jan. 22, 1959, Ser. No. 788,351

7 Claims. (Cl. 317—2)

This invention relates to the storage and transportation of fuels and in particular to the safe storage and transportation of fuels which tend to build up dangerously high static charges.

The handling of fuel for jet aircraft and similar fluids has presented many difficulties. With the development of special fueling techniques and fuel transportation procedures, an acute problem has arisen since, under certain conditions, jet fuels tend to build up high static charges with the concomitant probability of an electrical discharge of sufficient energy to cause an explosion. The determination of the mechanism of the build-up and discharge of static charges in such fuels and the provision of a means by which this obviously dangerous condition may be avoided has presented a major challenge to the field.

It is a primary object of the present invention to provide method and apparatus for the safe storage and transport of fuels for jet aircraft and the like. It is an additional object of the present invention to provide method and apparatus which effectively provide for the dissipation of static charges accumulating in jet fuels and similar fluids. It is a further object of the present invention to provide means in a fuel storage system for limiting the maximum energy level of electrical static discharge below that of the explosion level of the fuel vapor. It is a still further object of the present invention to provide a simple and economic means for safe storage for jet fuels and the like which may be utilized in a fuel storage system without interfering with the normal use of the system. These and other objects of the present invention will become apparent from the following description and drawings in which:

FIG. 1 is a view of a rolling fluid storage and transportation device;

FIG. 2 is a cross section of the axle of the device of FIG. 1;

FIG. 3 is a cross section of one form of an antistatic element according to the present invention;

FIG. 4 is a plan view of one form of the elements of FIG. 3 as it may be used in the fuel storage system;

FIG. 5 is another form of an antistatic element;

FIG. 6 is a view along line 6—6 of FIG. 2;

FIG. 7 is a detail of the apparatus illustrated in FIG. 4 as applied to an axle such as shown in FIG. 2;

FIG. 8 is a still further form of antistatic element;

FIG. 9 is a cross sectional view of an aircraft fuel tank having antistatic elements according to the present invention applied thereto; and

FIG. 10 illustrates a fuel storage tank such as used in a barge or similar device having antistatic elements mounted therein.

As previously mentioned, the build up of static charges in jet fuels poses a serious problem in the military and civilian air transport field. Because jet fuel is used in large quantities and transported substantial distances under extreme conditions, the possibility that a sufficient static charge may build up within the fuel and arc to cause an explosion must be seriously considered. It has been discovered that a static charge build up is most likely to occur in jet fuel storage and transportation systems when the fuel is severely agitated, a temperature differential exists between the fuel and the container or between different parts of the fuel, and the fuel is of high electric-

2

cal resistivity so that the static discharge cannot dissipate as rapidly as accumulated. With a fuel of a resistivity of 10^{12} ohm-cm. or higher under conditions of substantial agitation, a sufficiently high charge has been found to build up within the fuel so that an arc may occur across the fuel surface, usually to a metallic surface within or adjacent to the fuel container. However, it should be noted that it is not essential that a metallic surface be present in order for an arc to occur but that it is possible for sufficiently high charges to be built up so that a spark may occur between one portion of the fuel and another. For an explosion to occur it is necessary that the fuel vapor be mixed with air or some other source of oxygen and that the static discharge in the container have a minimum energy of approximately 200 microjoules. Under these circumstances, it has been found possible to cause explosive conditions in a fuel merely through the static charge built up while the fuel is being moved from one point to another in a rolling fuel container or in a fuel cell.

The present invention has been tested under a variety of operational conditions similar to those mentioned and it has been found to successfully prevent the accumulation of high static charges and eliminate discharges which may be sufficiently high in energy to attain a detonation level. While details of the present invention will be made clear in the subsequent explanation, the invention in general comprises providing, within the fuel or between the fuel and any highly conductive surface present which might catalyze a static discharge, a conductive path of a resistivity substantially below that of the fuel but substantially above that of a good conductor and a resistance sufficiently high to limit the maximum energy level of any discharge to a value below that which would detonate any fuel vapor present.

FIG. 1 illustrates a rolling fluid transporter designated generally by the numeral 1 which contains a quantity of jet fuel 2. The transporter 1 comprises a flexible inflatable elastomeric tank 3 having a metallic axle 4 extending therethrough. A towing frame 5 is coupled in conventional manner to axle 4 in order to facilitate overland movement of the tank. The axle 4 is provided with a plurality of cone-like antistatic elements 6 which will be described in detail subsequently. As the transporter 1 is rolled over the ground the axle 4 rotates causing the elements 6 to effectively scan or sweep a volume within the tank surrounding the metallic axle 4.

The axle 4 is shown in detail in FIG. 2 and comprises a horizontal preferably hollow tube 7 having hub plates 8 mounted at either end thereof and adapted to receive and retain the flexible tank 3 in much the same fashion as a tire is mounted on a wheel rim. The axle 4 is provided with a plurality of cone-like projections 6 covering the horizontal tube 7 and the interior face 9 and outer circumferential edge of the hub plates 8. The elements 6, which may be seen in detail in FIG. 3, comprise a generally conical body 10 extending upwardly from a flat unitary base section 11. In order to function as antistatic elements and satisfy certain electrical requirements which will be discussed later, the projections may be formed of a variety of materials, for example conductive rubber.

The individual conical bodies 10 of the antistatic elements may be cast or molded in large numbers in sheet form as illustrated in FIG. 4, and the individual sheets 12 provided with serrated end portions 13 which are adapted to fit together so that when a plurality of the sections 12 are placed on or about a surface they may be fitted with respect to each other to cover the entire surface, such as an axle as shown in FIG. 1. A similarly cast or molded section 14 comprising a substantially cir-

cular pad 15 having a plurality of conical projections 16 may be utilized on the face 9 of the hub plates 8 as illustrated in FIG. 6, the serrations on the molded base extending outwardly to serve as antistatic projections to protect the periphery of the hub. Of course, as will later appear, the conical antistatic elements may be manufactured as individual units and mounted on the desired surface in a variety of ways although the mode illustrated in FIGS. 2, 3, and 4 is preferable.

An alternative form of the antistatic element may be seen in FIG. 5 and comprises a generally flat sheet 17 having a plurality of downwardly extending substantially cylindrical projections 18 and adapted to be mounted on the surface of an axle 19 in such a manner that the projections 18 function as spacers to position the sheets 17 outwardly of the axle 19. The upper surface of sheets 17 will then perform substantially in the manner of the cones 10 to provide, as will be later explained, the requisite discharge path.

A mode of attaching molded or cast sheets such as those illustrated in FIG. 4 to a surface such as an axle is illustrated in FIG. 7. The sheets 20 and 21 are wrapped about the axle and positioned so that the serrated ends 22 and 23 fit intimately together. This assures that no substantial portion of the axle is left exposed. In order to minimize the possibility that a charge might arc to the axle beneath the crack or space at the conjunction of the serrated portions, the sheets may be manufactured with an antistatic projection such as 24 or 25 located at each point in the serrated area. As will later become clear, the size and location of these projections is such that the likelihood of an arc to the space between is extremely slight. Obviously the serrations may be omitted and a straight edge utilized if desired. The sheets may be removably attached to a surface by means of clips 26 such as illustrated or by means of screws, rivets, or semi-permanently mounted with any of a variety of adhesives.

FIG. 8 illustrates another form of the antistatic device made according to the present invention. For simplicity, the operation of the present invention will be discussed with respect to the element illustrated in FIG. 8, it being understood that multiple elements may be utilized comprising either a plurality of those illustrated in FIG. 8 or a sheet of elements as illustrated for example in FIGS. 3 and 4. In FIG. 8 a substantially conical element 27 having an enlarged base 28 is attached to a metallic or highly conductive surface 29 by means of a screw 30 embedded in the base 28 of element 27. The base 28 is provided with a raised tapered ridge 31 for reasons which will subsequently be explained. The element 27 together with its base 28 may be made of a number of materials, one of which is conductive rubber compounded to meet the desired electrical conditions. Subsequent explanation of the electrical phenomena involved and the conditions to be satisfied will clearly show that other materials may be used although conductive rubber has certain particular advantages for this purpose.

Referring to FIG. 1, assume that the rolling fluid transporter illustrated contains a quantity of a jet fuel, for example that usually designated JP-4, and that the tanker is rolled, as might occur in operation, over rough terrain so that considerable sloshing or agitation occurs in the fuel. Consider also that the fuel may have been transferred into the tanker from a subterranean storage facility so that the fuel is at a different temperature than the tanker. This condition will, after a time, give rise to temperature gradients within the fuel. It is important also to note that fuels such as JP-4 have a resistivity of about 10^{13} ohm-cm. and as such represent bad conductors, or conversely, good insulators. The build up or accumulation of static charge is thought to be due to the addition to a portion of the fuel of mechanical energy due to sloshing and/or thermal energy due to temperature differentials, so that different portions of the fuel have

greater or lesser tendencies to give up electrons or ionize. Those portions having higher energies will tend to lose their electrons to adjacent portions or droplets of the fuel. Since the fuel is a very poor conductor, and thus the charge cannot easily migrate to neutralize the ionized areas, a net charge will thus be built up upon the surface of or within an isolated portion of the fluid. Referring to FIG. 8, in the usual case where a highly conductive surface such as the axle 29 is present, a negative charge 32 in the fuel is mirrored at the conductive surface by an opposite positive charge 33. If the gradient becomes sufficiently high an arc will occur between charged areas 32 and 33 as illustrated by the arrows. If the axle 29 is exposed to the vapor of the fuel and the mixture is appropriately lean, an explosion can occur if the discharge energy exceeds about 200 microjoules. Since in experiments utilizing a transporter of this type it has been possible to cause static discharges measured at levels in excess of 500 microjoules, the danger of an explosion is substantial.

According to the present invention, a conductive path is formed, for example, by the element 27 in FIG. 8 is provided between the highly conductive axle and the fuel and having a current limiting resistance such that the maximum discharge energy is below the explosion level of the fuel vapors, i.e. 200 microjoules. However, it has been found that it is not sufficient merely to provide a path having a sufficiently high total resistance to limit the D.C. current because of what may be termed the capacitance effect of highly conductive surfaces such as axle 29. Without entering into a detailed theoretical discussion, it has been discovered that, in the presence of highly conductive material, the total D.C. resistance of the element 27 will not limit the sparking current level in the fashion of a simple D.C. circuit but that the presence of highly conductive material in any substantial amount will act as a low value reactance or a virtual short. One explanation for this is that the discharge or arc occurs over such a brief period of time and has such a steep wave front that it possesses the characteristics of a pulse of extremely high frequency alternating current. For this reason highly conductive materials, even though covered with an insulator of some thickness, exhibit a capacitive reactance character and act as a virtual short circuit to the A.C. pulse. This phenomenon is illustrated by the fact that a small piece of highly conductive material suspended by an insulator in space will freely arc to high static charge areas. Hence, the conductive path provided must have electrical properties to avoid such an occurrence. It has been found that in order to provide a safe non-arching path it is necessary that the resistivity of the antistatic path be of intermediate value, or between 10^5 and 10^9 ohm-cm. Broadly speaking, the element must be made of material having a resistivity substantially below the resistivity of the fuel, which is 10^{12} ohm-cm. or higher in fuels capable of building substantial charges, but substantially above that of the axle or other highly conductive surface present, the commonly encountered good conductors having resistivities in the range of a micro ohm-cm. to a milli ohm-cm. In order to meet this condition, the element 27 may be made of a substantial number of what might be termed semi-conductive materials such as loaded plastics, resins, or elastomers. However, preferred among them is conductive rubber which, due to its flexibility, may be easily installed on curved surfaces and easily manufactured by casting or molding. It is also preferred that materials such as conductive nitrile or polyurethane rubber be utilized since they are substantially unaffected by the fuels with which they come in contact.

Referring once again to FIG. 8, under the circumstances previously postulated if a net negative charge occurs at 32 and, as is required, the fuel as a whole has a zero net charge, then a net positive charge will occur in another portion of the fuel, for example at 34. Ordin-

narily this positive charge would be mirrored at the axle 29 and, once again, the possibility of dangerous arcing would be present. However, the element 27 presents a path of intermediate conductivity extending from the conductive axle 29 into the fuel container. The positive charge 34 is then mirrored by a negative charge 35 at the tip of the element 27 and current flow to the charge 34 due to local ionization is effectively limited by the total resistance of the element 27 to a value below 200 microjoules. As previously mentioned, the element 27 is made substantially wholly of material having a resistivity of intermediate value to avoid arcing due to the so-called capacitance effect of highly conductive materials. For this reason, it is essential that no substantial mass of highly conductive material be included in element 27 in any portion exposed to or closely adjacent the fuel. The element 27 is also preferably generally conical with the base of the cone mounted on the axle 29. The tapered character of the element increases partial ionization about the tip which results in a constant bleed of charge in a silent discharge to neutralize static charges building up in the fuel. The elements could, of course, be elongated, generally cylindrical members of rather small diameter, if desired, and substantially the same effect could be obtained. It should be noted that the polarity of the local charge in the fuel adjacent any conductive path provided by the elements 27 is unimportant since a charge of opposite sign will at once be supplied in limited rates from the element to reduce the discharge energy level.

The element 27 is illustrated as attached to axle 29 by means of threaded screw 30 embedded in the base thereof. In order to minimize any capacitance discharge effect caused by the screw and to reduce the possibility of arcing to the bare axle area between two adjacent elements, the enlarged base 28 may be provided with a tapered ridge or lip 31 which promotes partial ionization 36 in the area and reduces any local space charge 37 to below the danger point. It is understood, of course, that the device illustrated in FIG. 8 should be utilized in large numbers to substantially blanket any conductive surface to effectively shield it electrically from any charge in the fuel container. It has also been found that in order to avoid arcing to exposed metal conductor between adjacent elements the optimum condition is that the length of the elements 27 including the base 28 should be at least equal to or greater than the spacing between adjacent elements.

As mentioned, it has been found that the danger of explosive discharges due to static charge accumulation exists primarily in fuels having a resistivity of at least 10^{12} ohm-cm. Where a highly conductive surface such as a metal axle is present in or adjacent the fuel, the intermediate conductive path should be provided having a resistivity in the range of 10^5 to 10^9 ohm-cm. and preferably between 10^8 and 10^9 ohm-cm. In addition, the current limiting resistance of the element should be in the range of 50 to 500 megohms and preferably between 50 and 100 megohms. Slightly lower or higher values may be tolerated but only with a loss in safety factor. However, it is essential that the resistivity of the conductive path be substantially below that of the fuel and above that of any metallic conductor present.

Even though no highly conductive surface is present in the system, there is always the possibility that an arc can occur between differently charged areas of the fuel itself, and hence it is desirable to provide at least one conductive path, and preferably a plurality thereof, from one part of the fuel to the other to minimize the danger of arcing. In such cases the resistivity of the conductive path may be somewhat lower than the stated range so long as it does not substantially approach that of a good conductor. Nonetheless current limiting resistance of the path should, of course, be in the range mentioned to limit arcing energies to below the 200 microjoule level.

While the operation of the invention has been described in regard to the type of element illustrated in FIG. 8, the form illustrated in FIGS. 3 and 4 is preferred since it is simpler to mold sheets having a plurality of elements thereon. Such a form eliminates the need for metal mounting screws and hence reduces the possibility of a high energy arc due to the capacitance effect of highly conductive material. In addition, sheets of elements such as illustrated are easier to install and require less time and laborious tapping of the conductive surface in order to insert the screws.

FIG. 9 illustrates a typical fuel cell 38 having a filler neck 39 or similar fitting mounted thereon. In certain crash refueling procedures the fuel is forced into the cell and considerable agitation of the fuel occurs. In addition, the fuel may be severely agitated during rough flying conditions. In either case, the opportunity for a static charge accumulation is substantial and, hence, an explosion due to arcing is a danger. According to the present invention, a plurality of elements 40 similar to those illustrated and previously described are mounted on the highly conductive surfaces in and around the fitting 39 to minimize the possibility of an explosion. It is clear that the elements may extend into the container and orifice fitting without substantially interfering with the normal use of the cell.

FIG. 10 illustrates a fuel storage and transportation device such as a barge or a tank therein. The tank walls 42 may be made of metal or a metal coated on the interior with another less conductive material. In any case, because of the possibility of an arc due to capacitance effect previously mentioned, it is desirable to minimize the opportunity of the occurrence of a dangerous spark by providing a plurality of conductive paths of intermediate resistivity and limiting resistance by means of elements 43 similar to those previously described mounted on and shielding the walls of the container.

While certain representative embodiments and details have been shown for the purpose of illustrating the invention, it will be apparent to those skilled in this art that various changes and modifications may be made therein without departing from the spirit or scope of the invention.

I claim:

1. A system for storing and transporting high resistivity fuels with minimum risk of the occurrence of static discharges of energies exceeding the explosion level of vapors of said fuels comprising a rollable fluid container having fuel therein and having a highly conductive metallic axle therethrough, and a plurality of conductive elements mounted on said conductive axle and projecting into the interior of said container, said elements having resistivities substantially above that of said conductive axle and substantially below that of the fuel and resistances sufficient to limit the flow of electrical energy therethrough to a value below the explosion level of the vapor of said fuel.

2. A system as claimed in claim 1 in which the fuel has a resistivity of at least 10^{12} ohm-cm. and the elements have resistivities in the range of 10^5 to 10^9 ohm-cm. and resistances in the range of 50 to 500 megohms.

3. A system as claimed in claim 2 in which said elements are elongated in the direction substantially normal to said axle and are located thereon in spaced apart relation so that the length of said elements is at least equal to the space between adjacent elements.

4. A system as claimed in claim 3 in which said elements are substantially conical in shape with the base of the cone mounted on said axle.

5. A system as claimed in claim 4 in which said elements are composed substantially of conductive rubber.

6. A system for storing high resistivity fuels with minimum risk of the occurrence of static discharges of energies exceeding the explosion level of vapors of said fuels comprising a container having fuel therein and a highly

conductive surface in said container, and plurality of conductive rubber elements mounted in spaced relationship on said highly conductive surface and projecting therefrom into the interior of the container, said elements being substantially conical in shape with the base of said cone mounted on said conductive surface and having a resistivity substantially below that of the fuel and substantially above that of the conductive surface and a resistance sufficient to limit the flow of electrical energy therethrough to a value below the explosion level of the vapor of said fuel.

7. A system as claimed in claim 6 in which said conical elements are located so that the length of the elements is at least equal to the space between adjacent elements on said surface.
